UNITED STATES PATENT OFFICE.

DAVID H. OSBORNE, OF BALTIMORE, MARYLAND, ASSIGNOR TO LOCKE INSULATOR CORPORATION, OF BALTIMORE, MARYLAND, A CORPORATION OF MARYLAND.

METHOD OF MAKING FORGED INSULATOR CAPS.

Application filed May 28, 1925. Serial No. 33,538.

The invention relates to metal caps for insulators used for supporting high tension conductors.

It is well known that insulator caps are usually formed in the shape of an inverted cup with means at its top for connection with another insulator or with a supporting element, the cup being secured upon an up-standing neck on the insulator body; and 10 that the common practice is to form such caps as castings.

The principal object of the present invention, generally stated, is the provision of a method of making such caps by forging in 15 contradistinction to casting.

The object of the invention, more specifically stated, is to provide a forged cap of the socket type together with a method of forging or making the same.

20 Another object of the invention is to provide a novel method of securing in place the partition element which is located between the body or main portion of the cap and the socket which is provided for connection with a suspension bolt element of an adjacent insulator or of a support, the method avoiding upsetting of any portion 25 of the cap wall.

A further object of the invention is to provide a method of making forged caps in 30 which the operation will be simple and inexpensive and the number of steps and handlings considerably reduced.

To the attainment of the foregoing and 35 other objects and advantages the invention consists in the method to be hereinafter more fully described and claimed and illustrated in the accompanying drawings wherein:

40 Figure 1 is a perspective view of a blank from which the cap may be made,

Figure 2 is a vertical section through a pair of coacting dies in use and in the act of forming the cap,

45 Figure 3 is a sectional view through the cap formed by the dies, this view also illustrating two subsequent steps in the method,

Figure 4 is a fragmentary vertical section showing the method of inserting the 50 partition element or diaphragm,

Figure 5 is a similar view showing the diaphragm in final position,

Figure 6 is a vertical section through the

cap in active or applied position with the suspension bolt in place,

55 Figure 7 is a section on the line 7—7 of Figure 6 showing a plan of the cap,

Figure 8 is a section on the line 8—8 of 60 Figure 6 illustrating the retaining element for holding the bolt in place.

Referring more particularly to the drawings I have, in Figure 1, illustrated a cylindrical metal blank 1 from which the cap may be formed. Any preferred or necessary preliminary steps may be gone through with, if found advisable, in the working of the blank into the cap but in Figure 2 I have shown upper and lower dies 2 and 3 which are adapted to act upon the blank, either in the first place or after preliminary treatment, for the purpose of pressing it into the desired cup-like shape. The dies are of such nature and have such configurations that they will press the blank to define a cup-shaped body 4 having a reduced end portion 5 formed with a socket 6. In caps of the socket type the end portion 5 is formed with an opening 7 which is of elongated elliptical shape and which communicates with an opening 8 extending laterally from 70 the center thereof for a purpose to be explained. The upper die 2 is also so shaped as to define a shoulder 9 and a circular wall 10 having a flattened portion 11 on the inside of the cap adjacent the socket portion 6. 75 The lower die 3 has an extension portion 12 thereon which will define an inwardly pressed flat portion or surface 13 on the exterior and interior of the reduced end portion 5 of the cap. The upper die is of such 80 form as to define a shoulder 14 spaced from the shoulder 9 and located at a point opposite the flattened outer wall portion 13.

Subsequent to the forming of the cap by the dies, the larger end of the body is 85 crimped, spun or otherwise treated to provide a flange 15 which extends inwardly at an angle, and which coacts with the cement commonly used for securing the cap to an insulator body. A hole 16 is drilled through 90 the wall of the socket portion at the above mentioned inwardly pressed portion 13 for the reception of an element to be described.

In insulator caps of the socket type disclosed it is considered necessary to have a 100 partition between the body or main portion

of the cap and the socket portion and in accordance with this requirement I preferably make use of a disk or diaphragm 17 of resilient metal and of a size to be fitted very tightly within the confines of the wall 10 and against the shoulder portion 9 of the cap. At one edge of this disk is flattened or cut away along a straight line as indicated at 18 for engagement against the flattened interior surface of the cap, these two surfaces or portions acting as a guide to determine the position of the disk with respect to the cap. The reason for having guide means for determining the position of the disk with respect to the cap is that the disk is preferably initially formed with pressed out projections 19 arranged in spaced relation and adapted to serve as guides and retaining means for a spring cotter 20 which is provided for a purpose to be described. The disk is of such size that when initially inserted it will not fit in place and to force it into place some suitable plunger device 21 may be placed against the center of the disk and pressure applied so as to flex the disk as shown in Figure 4. Obviously, this flexure will render the disk temporarily concavo-convex in form and will have the effect of reducing the diameter so that the disk may be forced into place within the wall 10 and upon the shoulder 9. When this is done and the pressure subsequently relieved the resilient nature of the disk will cause it to resume its flat or planar condition, the diameter consequently increasing so that its periphery will bear firmly against the wall 10 adjacent the shoulder 9. In actual practice the holding action thus obtained is as secure, to all practical purposes, as if the disk were welded or otherwise held.

Insulator caps of this general character are ordinarily galvanized in order to provide them with a non-rusting coating so as not to be influenced by the weather, and in the present instance this galvanizing may be done before or after the partition disk is placed in position, this detail being immaterial.

Assuming that the cap has been formed and the disk placed in position, the cap may be secured upon the insulator body in the usual manner though such is not illustrated, as forming no part of the present invention. In practice, caps of this character are suspended by means of bolts having heads adapted to be inserted within the socket portions. In Figures 6 and 7 I have shown such a bolt 22 having a head 23 of circular shape. To assemble the bolt and cap, they must be canted with respect to each other so that the head 23 may be inserted edgewise through the opening 7, the stem of the bolt being located in the lateral opening 8. After the edge of the head has been inserted the bolt is rocked to withdraw the stem

portion from the opening 8 so that it may extend coaxially with the cap as shown in Figure 6, the head then engaging beneath the overhanging edges of the openings 7 and 8 as indicated in Figures 6 and 7.

To maintain the bolt against subsequent displacement, the above mentioned cotter 20 is inserted through the hole 16, the projections 19 on the disk serving as guide means. The arms 24 of the cotter will extend substantially entirely across the socket with their ends engaging beneath the shoulder 14. Displacement of the cotter in one direction will thus be prevented. The arms 24 of the cotter are preferably formed with outwardly extending humps 25 which will engage between the projections 19 on the disk and the inner wall of the socket at the flattened portion 13 so that accidental retraction of the cotter will be prevented. Obviously, when this cotter is in place the bolt cannot be rocked to a sufficient extent with respect to the cap to effect removal of the head through the opening 7.

From the foregoing description and a study of the drawings it will be apparent that I have thus provided a novel forged insulator cap and method of making the same, the cap being comparatively inexpensive inasmuch as the number of necessary steps in the method have been reduced to the minimum. An extremely simple method has been devised for effecting securing of the partition disk without welding or upsetting the material to provide retaining means. In previous methods the greatest difficulty has been encountered in placing and securing the partition disk in place and in this particular the present invention is especially advantageous on account of the ease with which the disk may be inserted.

While I have shown and described a preferred embodiment of the invention and details of construction and arrangement together with a statement as to the various steps involved and their sequence it should be understood that this disclosure is merely illustrative inasmuch as I reserve the right to make all such changes as will not depart from the spirit of the invention or the scope of the claims hereunto appended.

Having thus described the invention, I claim:

1. The method of making an insulator cap or the like, which includes forging a cup with a socket portion thereon and with an annular shoulder and an annular wall at the base of the socket portion, forging a partition member with guide portions thereon, forcing the partition member into engagement with said shoulder and wall and forming a hole in the socket portion for the reception of a retaining element insertable between the guides.

2. The method of making an insulator cap

- or the like, which includes forging a cup with a socket portion thereon having a slotted opening therein, forming a hole in one side of the socket portion, forging a partition member with spaced projections, forcing the partition member into the cup at its juncture with the socket portion and with said projections at opposite sides of said hole.
- 10 3. The method of making an insulator cap or the like, which includes forging a cup with a socket portion thereon having a slotted opening therein, forming a hole in one side of the socket portion, forging a partition member with spaced projections, forcing the partition member into the cup at its juncture with the socket portion and with said projections at opposite sides of said hole and inserting a spring retainer through 20 said hole to extend across the socket portion.
4. An insulator cap comprising an inverted cup-like body formed at its upper end with a socket portion having openings therein, a partition member at the base of the 25 socket portion, the partition member being formed with upstruck spaced projections and the side of the socket portion being formed with an opening between said pro-
- jections, a suspension element having a head located within the socket portion and having a shank extending through one of the openings, and a retaining element extending through said hole in engagement with the partition member and the head and located between said projections. 35
5. An insulator cap comprising an inverted cup-like body formed at its upper end with a socket portion having openings therein, a partition member at the base of the socket portion, the partition member being 40 formed with upstruck spaced projections and the side of the socket portion being formed with an opening between said projections, a suspension element having a head located within the socket portion and having a shank extending through one of the 45 openings, and a retaining element extending through said hole in engagement with the partition member and the head and located between said projections, said retaining element having oppositely extending humps engaging between the projections and the adjacent wall of the socket portion. 50

In testimony whereof I affix my signature.

DAVID HENRY OSBORNE.
